SPORT SHIRT

Murray Lesser, Brooklyn, N. Y.

Application September 22, 1939, Serial No. 296,015

1 Claim. (Cl. 2—116)

This invention relates to wearing apparel and particularly to an improved sport shirt, an object being to provide a construction which will present a neat pleasing appearance when buttoned.

Another object of the invention is to provide a sport shirt having a collar and extension therefrom which will present a pleasing appearance when the shirt is in use with the collar part of the shirt open.

Another object of the invention is to provide a sport shirt wherein the collar is provided with integral extensions arranged to underlap the front sections of the shirt as well as the sections adjacent the collar opening for providing a reinforcing and padded structure which functions to cause the outer part of the garment to be smooth and uniform in appearance.

In the accompanying drawings—

Fig. 1 is a perspective view of a sport shirt 20 disclosing an embodiment of the invention, the same being illustrated on a figure;

Fig. 2 is a view of the sport shirt shown in Fig. 1 spread out and viewed from the interior;

Fig. 3 is an enlarged fragmentary sectional view through Fig. 2 approximately on the line 3—3;

Fig. 4 is an enlarged fragmentary sectional view through Fig. 2 on the line 4—4;

Fig. 5 is an enlarged fragmentary sectional view through Fig. 2 on the line 5—5;

Fig. 6 is a view showing the patterns of the collar, collar extensions, inner strip of the front of the shirt, and the sleeve.

Referring to the accompanying drawings by numerals, 1 indicates the sport shirt as a whole, which is provided with sleeves 2 and 3 and a body 4 having front sections 5 and 6 and a back section 7. The sleeves 2 and 3 are shown as short sleeves but if desired they could be made long without departing from the spirit of the invention. When these sleeves are inserted into the body the edges are caused to overlap as indicated by the numeral 8 in Fig. 5 and a binding tape 9 is positioned to straddle the overlapped parts. A line of stitching 10 secures all these parts together, thereby presenting a strong and neat structure. After this has been done a finishing seam 11 is provided.

The back 7 extends upwardly and is provided with an upper top edge 12 forming part of the neck opening. Also the upper end of the back 14 is provided with shoulder extensions 13 and 14 as shown in Fig. 1 which meet the upper edges 55 of the front panel sections 5 and 6 to which

they are stitched by suitable lines of stitching. The front sections 5 and 6 are adapted to overlap and be removably connected by suitable buttons or other suitable disengageable means 15. The collar 16 is connected to the adjacent parts of the front sections 5 and 6 and to the back 7 at the neck portion 12 by suitable lines of stitching. The collar 16 is provided with a rear collar section 17 stitched to the front collar section 18 by suitable lines of stitching. The front collar section 18 merges into extensions 19 and 20 as shown in Fig. 6. These extensions form what may be termed lapel portions 21 and 22 and lapel extensions 23 and 24. The lapel extensions are substantially V-shaped as shown in Fig. 6. Tackings 25 and 26 connect the points or apexes 27 and 28 to the back 7 near the arm openings as shown in Fig. 2. By reason of this construction the front or outer surface of the collar 16 forms a continuous smooth surface 20 downwardly to the respective inner panels 29 and 30, which are secured to the extensions 19 and 20 by suitable lines of stitching 31 and 32. The outer edges of the panels 29 and 30 are connected by respective lines of stitching 33 and 34 to the front vertical edges of the sections 5 and 6 while their inner edges are left unstitched.

When the sport shirt is open as shown in Fig. 2 the collar 16 merges into the extensions 19 and 20 and presents a very pleasing appearance. When the shirt is in use and the first button or two are unfastened and the parts thrown back, the extensions 19 and 20 will be seen to a large extent and present a finished appearance to the shirt at and adjacent the neck portion thereof. In addition, when the shirt is buttoned as shown in Fig. 1 the extensions 19 and 20 form reinforcing and padded members adjacent the collar opening beneath the sections 5 and 6 and part of the shoulder extensions 13 and 14, whereby a smooth uniform appearance is provided. The respective lines of stitching 33 and 34 extend along the outer edges of the extensions 19 and 20, as well as around the outer edges of the collar 16. As shown in Fig. 3, the inner edge portions of the members 19 and 20 are loose or free from the front sections but provide a limited stiffening action for the front of the shirt, whereby it will hang properly when open and also present a pleasing appearance when closed as shown in Fig. 1. In addition, there is provided a lining 35 in back of the panels 29 and 30 and also in back of the extensions 19 and 20 and between the collar 16 and the collar section 17, whereby a desired firmness is secured which will hold the

parts in their desired position even though the material used may be very flexible.

I claim:

A sport shirt including a back formed with a central top edge and a pair of straight shoulder edges extending from the top edge to the sides of the back, a pair of front sections having straight front edges, said front sections being connected along one of their respective edges with the side edges of said back, said back and front sections being formed with arm openings, and a collar connected to said back and front sections at the top thereof, said collar having a

projection at each end, said projections extending along the inner edges to the front sections to form reinforcing panels acting as interior supports for the front sections when the shirt is in use, one edge of the respective projections being stitched to the front sections along their respective edges and one end of the respective projections extending along said shoulder edges and tacking for connecting one corner of the respective extensions to the front section at said shoulder edges near said arm openings.
